UNITED STATES PATENT OFFICE.

GEORGES CHARBONNEAUX, OF LE MAGNOU, PAR AIGREFEUILLE D'AUNIS, FRANCE.

ELECTROLYTIC CELL.

1,296,046.

Specification of Letters Patent.

Patented Mar. 4, 1919.

Application filed March 8, 1917. Serial No. 153,504.

To all whom it may concern:

Be it known that I, GEORGES CHARBONNEAUX, of Le Magnou, par Aigrefeuille D'Aunis, Charente-Inférieure, France, have invented a new and useful Improvement in Electrolytic Cells, which improvement is fully set forth in the following specification.

Graphite anodes are frequently employed for the manufacture of various products by electrolysis and particularly for the manufacture of the oxygen compounds of chlorin from chlorids. Other anodes formed of various alloys such as those having ferro-silicon for their base or cast metallic oxids are also employed.

In all cases the anodes pass into the electrolyte from the top of the cell, or through holes formed in the lateral walls or in the bottom of the cell.

These arrangements have the following disadvantages:

As a considerable portion of each anode lies outside the bath or is embedded in the walls of the cell, it is not utilized, thus uselessly increasing the cost of installation and maintenance.

As the electrodes are in contact both with the electrolyte and with the liberated chlorin and also with its metal conductors they must, especially when of graphite undergo a suitable treatment to avoid being attacked by the current. Moreover, as the electrodes are near together, it is usually difficult to obtain good joints between them and the cell, and this is the cause of great annoyance.

This invention relates to a novel arrangement of electrodes designed to overcome these troubles.

The invention is illustrated in the accompanying drawing, in which Figure 1 is a horizontal section of a cell taken on the line A—A of Fig. 2, Fig. 2 is a vertical transverse section on the line B—B of Fig. 1, and Fig. 3 is a vertical transverse section showing a modification.

The anode plates *a* and *b* are formed of graphite, metal, a metal alloy or a metallic oxid.

The left hand plates *a* alternate with the right hand plates *b* and their overlapping ends are pressed together to two terminals *c* *d* made from one of the materials above

mentioned or from some other suitable material.

The terminals *c* *d* pass through the wall of the cell and receive current from the conductors *e* *f* located outside the bath.

The plates are pressed together by a suitable arrangement situated outside the bath for example, by means of two U irons with tightening bolts above and below the bath or by means of bolts passing through the anodes themselves and insulated therefrom by glass tubes, paint or some insulating substance as illustrated by a tube *B* made of glass, micanite, or any other insulating substance.

The plate *g* *g*¹ of the cathodes *h* *h*¹ are arranged between the anode plates.

In place of the plates shown in the drawing the electrodes may consist of rods, bars or the like.

The terminals may be of prismatic or other shape; they are two in number or a multiple of two and are sealed in the wall of the cell by any convenient means.

It is evident that the arrangement alone described although principally devised for the manufacture of the oxygen salts of chlorin is applicable for the manufacture of various electrochemical products obtained by anodic oxidation.

The arrangement of electrodes herein described, has the following advantages:

The anodes do not pass through the walls of the cell, thus causing an important economy in material forming the anodes and a great diminution in the number of joints. As the terminals alone touch the current leads they also alone require a special preparation for protection against the action of the chlorin.

The joints are easy to make.

Claims:

1. In an electrolytic cell of the character described, electrodes consisting of alternating right and left hand plates whose ends overlap, terminal members adapted to pass through the walls of the cell and associated with the overlapping ends of said plates and means for clamping said terminals and overlapping ends together.

2. In an electrolytic cell of the character described, electrodes consisting of alternating right and left hand plates whose ends

overlap, terminal members adapted to pass through the walls of the cell and associated with the overlapping ends of said plates and a clamping bolt passing through said terminals and overlapping ends and a tube for insulating said bolt from said plates and terminal.

In testimony whereof I have signed this specification in the presence of two subscribing witnesses.

GEORGES CHARBONNEAUX.

Witnesses:

CHAS. P. PRESSLY,
GASTON DE CESTRAL.
